NECKTIE AND METHOD OF MAKING THE
SAME

William B. Rose, New York, N. Y.

Application February 14, 1936, Serial No. 63,826
Renewed June 19, 1937

4 Claims. (Cl. 139—384)

This invention relates to neckties and methods of making the same and more particularly to integral ties having greater warp density in their central portions, for example in the neckband and knot portions than at their ends.

The principal objects of the invention are to provide novel and advantageous neckties of the general character specified and novel and advantageous methods of making the same.

Heretofore, there have been made ties in which the warps are brought closer together in certain portions, such as the neckband portions and the knot portions, and the ties narrowed accordingly. In these ties the number of warps is substantially the same throughout the length of each tie. From a practical standpoint, however, it has not been practicable to vary a width of the tie enough to make the widest portion of the tie much more than twice as wide as the narrow portion. These ties, therefore, do not meet the usual requirements of the trade, namely that the wide portion be from three to four times the width of the narrow portion. It is therefore another important object of the invention to provide an integral necktie having the required variation of width and a greater warp density in the narrow portion of the tie than in the wide portion.

Preferably, in carrying out the present invention, the tie from the narrow portion thereof is widened, by spreading the warp, to as great a width as practicable and then additional warps are added at the sides to produce a further increase in width. Although for convenience the making of the tie has been described as being a widening operation, the making of the tie might just as well be described as starting from the wide part, eliminating side warps until the proper point is reached, and then crowding the warps closer together to further reduce the width and at the same time produce a greater warp density thus providing a superior neckband and knot portion. Ordinarily the tie would widen in each direction from the neckband and knot portions. The tie may be solid throughout, tubular throughout, solid in one part and tubular in another. The tie may be used as woven or when tubular may be turned so that the inside will be exposed.

Other objects, features and advantages will appear upon consideration of the following detailed description and of the drawing in which

Fig. 1 is a diagrammatic view illustrating one form of the tie and the method of making it; and
55 Fig. 2 is a section on the line 2—2 of Fig. 1.

In the embodiment of the invention illustrated, use is made of a central group of warps 10 and edge groups of warps 11 in combination with weft thread 12 to form a tubular necktie 13 or the like. Considering the weaving as starting at the left hand or widest portion the tube is woven in the usual manner except that warps 11 are dropped gradually at the edges so as to reduce the width of the tie very gradually until all of the warps 11 of the edge group have been dropped (at the line A). Then the warps 10 are gradually brought closer together to narrow the fabric from the line A to the line B, thus increasing the warp density in the knot portion 14 and producing a maximum warp density in the neckband portion 15 from the line B to the line B'. At the farther end of the neckband portion 15 the warps 10 are again spread to widen the tie. If desired use may again be made of warps 11 to increase further the width of the short end of the tie.

The use of the edge warps 11 may be controlled by jacquard mechanism and the variation in the closeness of the warps 10 may be produced by use of a fan-shaped reed. The tie may be provided with any suitable pattern and in some instances the pattern may be woven on the inside where the tie is to be turned inside out.

It should be understood that various changes may be made in various features and certain features may be used without others without departing from the true spirit and scope of the invention.

Obviously by the use of shiftable shuttle boxes it will be easy to shift from one kind or color of weft to another.

Having thus described my invention, I claim

1. An integral woven necktie comprising a neckband portion consisting of weft and closely spaced warps in substantially parallel arrangement, a knot forming portion consisting of weft and gradually diverging continuations of the neckband warps, and an end portion gradually increasing in width and the warps of the neckband and knot forming portions in parallel and spread relation, and additional warps at opposite sides of the parallel continuations of the warps of the neckband and knot forming portions.

2. An integral woven necktie hollow throughout its length to enable it to be turned inside out, comprising a gradually tapered body portion consisting of weft and a plurality of parallel warps of which the termination of successive edge warps provides the taper, a tapered knot portion

consisting of weft and the remaining warps of said body portion in converging relation, and a neckband portion consisting of weft and parallel continuations of the warps of said knot portion in compact arrangement.

3. An integral woven necktie hollow throughout its length to enable it to be turned inside out, comprising a gradually tapered body portion consisting of weft and a plurality of parallel warps of which the termination of successive edge warps provides the taper, a tapered knot portion consisting of weft and the remaining warps of said body portion in converging relation, a neckband portion consisting of weft and parallel continuations of the warps of said knot portion in compact arrangement, and a short portion around which the knot portion may be tied, said short portion consisting of weft and continuations of the warps of said neckband portion in diverging arrangement.

4. An integral woven necktie hollow throughout its length to enable it to be turned inside out, comprising a gradually tapered body portion consisting of weft and a plurality of parallel warps of which the termination of successive edge warps provides the taper, a tapered knot portion consisting of weft and the remaining warps of said body portion in converging relation, a neckband portion consisting of weft and parallel continuations of the warps of said knot portion in compact arrangement, a short portion around which the knot portion may be tied, said short portion including a flaring length consisting of weft and diverging continuations of the warps of said neckband portion, and a second flaring length beginning at the wide end of the first length and consisting of weft, parallel continuation of the warps of said flaring length and additional edge warps.
